UNITED STATES PATENT OFFICE

FREDERICK W. LINAKER AND THEODORE M. BRUBACK, OF DU BOIS, PENNSYLVANIA

SOOT CLEANER

Application filed May 24, 1923. Serial No. 641,149.

This invention relates to devices for cleaning the tubes of boilers, economizers and the like, commonly known as soot-cleaners, and aims to provide improvements therein.

5 The invention provides improvements in the type of soot cleaners where the valves are located close to the cleaner element, and both the valves and element are operated by a single operating means, as disclosed in the patent 10 of Frederick W. Linaker, No. 1,413,601, granted April 25, 1922, to one of the present applicants.

In the present improved construction, the opening and closing of the valve is automatically effected, through the operation of a single means which operates both the valve and the element, the entire structure being simple in construction, compact and reliable. The present invention provides a construction 15 for accomplishing the same general purpose as the invention set forth and claimed in our application Serial No. 631,644, filed April 12, 1923, but which is another means and which is simpler.

20 An embodiment of the invention is illustrated in the accompanying drawings, in which

Figure 1 is a longitudinal sectional view showing the head and so much of an element 25 as is necessary to show the invention, the section being on line 1—1, Fig. 2.

Fig. 2 is an end view of the head, with the cap removed, and with the valve in closed position.

30 Fig. 3 is a view similar to Fig. 2 showing the valve partly open.

Fig. 4 is a view similar to Figs. 2 and 3 and showing the valve completely open and in the position in which the element is rotated 35 to perform its cleaning operation.

Fig. 5 is a sectional view on the line 5—5, 40 Fig. 1, and showing clearly the valve seat.

Referring to said drawings, numeral 10 designates the cleaner or blower element, which 45 projects through the wall 11 of a furnace or the like, and which is provided with a series of nozzles (not shown) through which jets of steam are projected to perform the cleaning of soot from the boiler tubes, in well known manner.

Steam (or other suitable fluid) from any suitable source is supplied through a pipe 15 to a head 17, which has a valve 19 therein for controlling the flow of steam to and from the element 10.

55 The element 10 has a turning connection with said head 17, as a stuffing-box connection 21, and is rotated by suitable means, as by means of a sprocket wheel 23 fixed on said element, over which sprocket wheel an endless hanging chain (not shown) is ordinarily passed.

The valve 19 consists of a valve member 30 and seat member 31, the latter being fixed on an end of said element 10, and having an orifice 33 (Fig. 5) through which steam is admitted to the element 10. The valve member 30 is carried on said seat member 31, and is slidable to and from a position opening and closing the orifice 33, for which purpose suitable means 35 are provided within the head 17 and connecting with the element 10 in such manner that the turning of said element 10 by its operating means 23 effects the opening and closing of the parts of the valve 75 19. The means 35 includes an annular surface 46 and a recess 48, as will be described.

The valve member 30 is conveniently pivoted to the valve seat 31, as by means of an eccentric pin 37 passing through said valve member and screwed into said seat member 31. The valve member 30 has an arm or extension 40, which is conveniently forked to accommodate a roller 42, and which arm contacts with a stop 44 on the head 17 to turn said valve member to open position when the element 10 is turned in a counter-clockwise direction (Fig. 2). In Fig. 3 the valve is shown in partly open position. The roller 42 is adapted to ride over said stop 44 after the valve has been opened, and beyond said stop 44 the head 17 is provided with guiding means, as the inner wall 46 of the head, for restraining said arm 40 to prevent it from moving in a direction to close the valve while the element 95 is being turned back and forth (see Fig. 4) to blow or clean the tubes of the boiler. In front of the stop 44 there is a recess 48 in which the arm 40 is adapted to project in the closed position of the valve (as shown in 100

Fig. 2) and opposite the stop 44 there is a stop 50 against which a projection 52 on said arm 40 is adapted to strike when the arm, on the return movement of the element 10, is moved over and beyond said stop 44. This stop 50, on the continued movement of the element 10 in a clockwise direction after the projection 52 makes contact therewith, acts to turn said arm 40 to turn the valve member 30 to a position closing said orifice 33, and thus to close said valve, and stop the flow of steam to the element 10. As the projection 52 extends beyond the roller 42 on arm 40, a groove 54 is provided therefor in the inner wall of the head 17.

A plate 56 is conveniently provided on the seat member 31 between which and the said seat member the valve proper slides and is housed. This plate 56 is conveniently supported and held in spaced relation to the seat member, by means of posts 58, 59, 60 having nuts 62 thereon for fastening said plate on said posts. The posts 58 and 60 also serve as stops for limiting the movement of said valve member 30 after it has been fully opened and fully closed. Opposite the orifice 33, the plate 56 is preferably provided with a corresponding orifice 64.

For the purpose of making a tight joint with the valve seat the valve member is provided with a recess or opening 66 within which is fitted a valve disk 68, of suitable material such as Monel metal, of somewhat greater diameter than the orifices 33 and 64, and the disk 68 is normally pressed toward valve seat 31 by means of a spring 70 housed in said recess 66 and bearing against the back of said disk 68.

Our present construction resembles that set forth, in our said application No. 631,644, in that the valve is mounted internally within a chamber formed by the head which intervenes between the steam admission pipe and the cleaner element or blower tube, the latter turning within said head. The general operation is the same, that is to say, the element moves from an initial inactive position, turning in one direction through an arc which may be varied according to location, and then backward to the initial position; in the inactive position the valve is closed, and in the initial movement it is opened, being thereafter held open during the rotation of the element, and as the latter is finally restored to its inactive position, the valve is automatically closed. The present construction differs from those set forth in said application in several respects; in the earlier constructions the valve consists in each instance of two members, one of which is carried with the blower element, and the other has a limited relative movement, being stationary during the initial movement of the blower element until the valve ports are opened, and thereupon the two members are locked to-

gether so that they both turn with the blower element, the lock being released near the end of the return movement of the blower element, and the relatively movable valve member striking a stop which holds it stationary during the final movement of the blower element, whereby the respective valve ports are closed. In the present construction, however, there is no lock uniting two valve members, but the valve proper or valve disk 68 slides relatively to the valve opening or seat 33, in the seat member 31, which turns with the blower element and is moved by a valve member 30 which is operated by an arm 40 in such manner as to communicate movement to open or close the valve in the initial and final movements of the blower element from and to its inactive position. This arm is pivoted eccentrically to the axis of rotation of the blower element, and therefore eccentrically to the retaining member, which in the construction shown is the inner face 46 of the head, and which is preferably concentric with the said axis of rotation. The movements of the arm, and consequently of the valve member, are accomplished by its entering or leaving the recess 48, being performed by the opposite stops 50 and 44, and after passing the latter, the arm (or its anti-friction roller 42) by traversing the concentric retaining member 46, is by reason of its eccentric pivot 37, held in position to retain the valve open during the entire rotary movement of the blower element. A desirably quick movement is given to the valve proper 68, since its motion is in the contrary direction to that of the valve seat which is turning with the element 10, thereby substantially doubling its speed of opening. This renders it possible to employ the simple form of sliding disk valve shown, instead of a valve having multiple radial ports, as in our said previous application. The improvements herein set forth considerably simplify and cheapen the valve and its operating means.

The invention may receive other embodiments than that herein specifically illustrated and described.

What is claimed is:

1. A tube cleaner comprising a cleaner element, a supply pipe, an intervening head forming a chamber, a valve within said head controlling flow from the pipe into the element, operating means for turning the element from and toward an inactive position of rest, and means for opening or closing the valve operated by such turning, comprising a moving part connected with the valve, and a stationary retaining member and stop for engaging said moving part, adapted respectively to hold it to maintain said valve in the open position, and to move it to open or close said valve as the element is turned into or from its inactive position.

2. A tube cleaner according to claim 1, the

moving part traversing said retaining member as the element is turned through its operative arc.

3. A tube cleaner according to claim 1, the moving part connected with the valve being pivoted eccentrically to the axis of the element.

4. A tube cleaner according to claim 1, the moving part connected with the valve being an arm pivoted eccentrically to the axis of the element.

5. A tube cleaner comprising a cleaner element, a head within which one end of said element turns, a valve in said head comprising a valve member and a valve seat carried by said element, and means in said head coacting with said valve member to move the latter to open and closed position when the element is turned, said means comprising an arm connected to said valve member and a stop for moving said arm over which said arm is adapted to ride when said element is turned in a direction to open said valve, and means for positively holding the valve in its open position after opening.

6. A tube cleaner comprising a cleaner element, a head within which one end of said element turns, a valve in said head comprising a valve member and a valve seat carried by said element, and means in said head coacting with said valve member to move the latter to open and closed position when the element is turned, said means comprising an arm connected to said valve member and a stop for moving said arm over which said arm is adapted to ride when said element is turned in a direction to open said valve, and a second stop against which said arm is adapted to abut after passing said first stop on the return movement of said arm when said element is turned in a direction to close said valve.

7. A tube cleaner comprising a cleaning element, a head within which one end of said element turns, a valve in said head comprising a valve member and a valve seat carried by said element, and means in said head coacting with said valve member to move the latter to open and closed position when the element is turned, said means comprising an arm connected to said valve member and a stop for moving said arm over which said arm is adapted to ride when said element is turned in a direction to open said valve, and a second stop against which said arm is adapted to abut after passing said first stop on the return movement of said arm when said element is turned in a direction to close said valve, and means beyond said first stop for preventing return of said arm while being moved beyond the position where the valve is opened.

8. A tube cleaner comprising a cleaner element, a supply pipe, an intervening head forming a chamber, a valve within said head

controlling flow from the pipe into the element, and operating means for turning the element, said valve including a valve seat member carried by the element, and a valve member pivoted thereto and having a projecting arm, and a stationary retaining member and stop within the head engaging said arm to move it as the element is turned to or from its inactive position, and to hold it in the open position of the valve during the active rotation of the element.

9. A tube cleaner comprising a cleaner element, a supply pipe, and an intervening head forming a chamber, the interior of the head formed with a stationary retaining member and with a recess having stops, the element carrying within said head a valve seat member having an eccentric seat, a valve movable over said seat, and an oscillating arm associated with the valve eccentrically pivoted and having portions for engaging such stationary retaining member and stops for operating the valve.

10. A tube cleaner comprising a rotary cleaner element, a supply pipe, and an intervening head forming a chamber, the interior of the head formed with a stationary retaining member and a recess having shoulders, the element carrying within said head a valve seat member having an eccentric seat, a valve movable over said seat, and a lever arm, eccentrically pivoted to said seat member, carrying the valve on one side of its pivot and having an arm on the opposite side of its pivot, the latter arm engaging said retaining member and recess, and engaged by said shoulders for turning it, whereby the valve moves oppositely to the seat to afford quick opening or closing.

11. A boiler tube cleaning apparatus, comprising a rotary cleaner element, a valve seat carried by said element, said valve seat being eccentric to the axis of rotation of the cleaner element, a valve member slidably movable across said valve seat to close it and open it, and means for operating said valve member and cleaner automatically, one with the other, said valve member and cleaner moving in opposite directions to open the valve.

12. A boiler tube cleaning apparatus, comprising a rotary cleaner element, a valve seat carried by said element, said valve seat being eccentric to the axis of rotation of the cleaner element, a valve member slidably movable across said valve seat to close it and open it, means for turning said cleaner, and means operated by the turning movement of said cleaner to actuate said valve in a direction opposite said turning movement.

In witness whereof, we have hereunto signed our names.

FREDERICK W. LINAKER.
THEODORE M. BRUBACK. 130
